UNITED STATES PATENT OFFICE.

MATTHEW H. LOUGHridge, OF BOGOTA, NEW JERSEY.

RAIL BOND.

Application filed October 25, 1920. Serial No. 419,201.

To all whom it may concern:

Be it known that I, MATTHEW H. LOUGHridge, a citizen of the United States, and a resident of Bogota, in the county of Bergen 5 and State of New Jersey, have invented certain new and useful Improvements in Rail Bonds, of which the following is a specification.

This invention relates to rail bonds, that 10 is, to a means for providing electrical conductivity for the joints of a railway track such as are required where track circuits are used either for propulsion current or for block signal purposes, and it has for an object 15 to reduce labor and material thereby effecting a savings in cost of this work and, in addition, providing a more direct contact with the rails and a higher conductivity bond. These objects are obtained by the 20 construction described in the following specification and illustrated in the accompanying drawings, in which Fig. 1 shows a rail joint with these bonds in place, Fig. 2 shows a section of the rail with the ends of the bond 25 wires before they are driven tight in the rail, Fig. 3 is a view corresponding to Fig. 2, with the bond wires driven tight in position, Figs. 4, 5 and 6 are developed cross-sectional views taken from Fig. 2, Fig. 7 is an outline 30 of the bond wires complete, Fig. 8 shows a development of this invention applied to a rail joint and using three bond wires, Fig. 9 is a view of the bond wires in place with the 35 rail in section, Figs. 10, 11 and 12, are developed cross-sections taken from Fig. 9, Fig. 13 shows how the ends of the bond wires 40 may be formed, Fig. 14 shows the end of the locking bond wire, Figs. 15 and 16 show the formation of both ends of two of the bond wires and Fig. 17 shows the formation of both ends of the locking bond wire.

It is well-known that the splice bars of a 45 rail joint are not reliable as conductors for the formation of an electric circuit through the rails of a track and the usual procedure is to provide a conductor bonded into each end of the rail which bridges the joint. This conductor or bond is securely fastened at each end in holes drilled in each end of 50 the rails, thereby making a continuous metallic path for the electric current. Established practice has shown that bonds made of a plurality of wires are more reliable and can stand the vibration of a railroad track much 55 better than a single conductor bond made from heavy stock. According to the present

invention, as illustrated in Fig. 1, two such conductors or bond wires are used and in Fig. 8, three bond wires are used around the joint.

Heretofore, it has been common practice to 60 drill a hole in the rail, insert the end of the wire in the hole, provide a tapered channel pin with a groove for the bond wire which fits the hole snugly and forms a tight joint 65 when driven into the rail. This required a separate hole for each end of each bond wire and a channel pin for each hole. The present invention eliminates the channel pins entirely and provides for securing the bond 70 wires in one hole in the end of each rail. This is secured by inserting the ends of both wires shaped according to the present invention, in said holes and by moving one relative 75 to the other these wires become securely locked in the hole without channel pins or other medium.

In the drawings, 11 represents the ends of 80 two abutting rails at a joint secured by the splice bars 12; 13 and 14 represent the bond wires secured in a hole in the end of each rail. In Fig. 2, it will be noted that wire 14 has an enlarged end 21 tapering inwardly to 22 and from this point the wire gradually 85 assumes the circular formation shown in Fig. 4. On the other hand, wire 13 tapers in the opposite direction from 24 with the smaller end at 23. When the end of wire 14 is inserted in hole 25 to the point indicated 90 at 22, there is sufficient clearance for the end of wire 13 to be slid into the same opening as indicated by the dotted line in Fig. 6. If, when in this position, wire 14 is driven 95 back on the end to the position shown in Fig. 3, then wires 13 and 14 snugly fit the hole in rail 11 and are securely locked or wedged therein, thus making a secure connection to the rail which makes direct contact with the rail and thereby provides increased conductivity.

It will be noted from Fig. 4, that the 100 wires are circular in cross-section while in Fig. 5, they each approach a semi-circle, and in Fig. 6 become a complete semi-circle, filling the hole 25. This hole is slightly 105 smaller in sectional area than the combined areas of wires 13 and 14 and these wires are wedged in a press to the semi-circular form shown, thus providing a closely fitting connection between the bond wires and the rail.

The slope of the end of wire 14 from 21 110 to 22 is preferably slightly greater than the

slope of wire 13 from 24 toward 23. Under ordinary conditions the friction between, wire 13 and the hole 25, is greater than the friction between the flat surface of the wires 5 themselves and wire 13 does not move when wire 14 is driven back. However, should wire 13 slide back on wire 14, this difference in taper would insure a wedging or locking effect of the wires in the hole. It will be 10 noted that the end 21 of wire 14 is circular in cross-section and is therefore easily driven back by a hammer to the wedging position.

When two wires are used the ends of the 15 wires are reversed one end being the locking wire and the opposite end being the wedge. For instance, in Fig. 7, it will be noted that wire 14 is shaped at one end with the wedge 23 and the opposite end with the 20 lock 21 and is positioned against wire 13 which is exactly similar with its ends reversed. Hence, all wires are made alike and are simply assembled with their ends reversed, that is, the end of one wire is made 25 the complement of its companion which together form a circular cross-section filling the hole in the rail.

In Fig. 8, 11 indicates a rail joint with the abutting ends of rails 11 secured by 30 the splice bar 12 and having the bond wires 31, 32 and 33 secured in the same hole in each end of the rail as shown. Two of these bond wires, 31 and 32 are preferably made alike, as shown in side elevation in Fig. 35 15 and in plan in Fig. 16. The ends of these wires slope outwardly as indicated from 38 to 35, Fig. 13, having a contour forming approximately 120 degrees of a circle as indicated by the diagram to the right, and the 40 locking wire is designed with a complementary contour as indicated in Fig. 14, from 36 to 34, sloping in the opposite direction to lock these two wires in the hole. From Fig. 10, it will be noted that these wires are 45 circular in cross-section, gradually developing as shown in Fig. 11, to the circle indicated in Fig. 12, where each wire forms approximately 120 degrees of the circular cross-section of the hole. The locking wire 33 is 50 inserted in the hole to position 34, then the wires 31 and 32 are inserted as far as possible when wire 33 is driven back, locking the three wires securely in the hole. The 55 end of the locking wire 33, it will be noted from the diagram to the right of Fig. 9, and Fig. 17, closely approaches a circle and is therefore able to take up the thrust of the hammer when driven into the locking position.

60 This bonding not only provides a direct contact between the bond wires and the rail, but enables the bond wires to be secured to the rail with the smallest possible hole, the hole in the rail being slightly less than the 65 combined areas of the wires, thereby effect-

ing a very material saving in the drilling of the rail and enabling a bond wire of larger size to be used in a smaller hole than would be possible with the use of channel pins.

It has been found that bond wires of this 70 class, particularly when made of a small sized wire and terminating in an abrupt and rigid connection with the rail are subject to crystallization due to the vibration of the rails. With the type of bond wire 75 shown in the present invention, this condition is largely overcome by gradually tapering the wire which is semi-circular in shape into a circular shape, distributing the effects of vibration over a greater area and 80 also as these wires are larger for the same rail drilling than wires using channel pins, they have a greater moment of inertia and thus are less influenced by vibration.

Having thus described my invention, I 85 claim:

1. In a rail bond, a plurality of wires each of substantially the same sectional area throughout, said wires shaped near each end to have a cross-section forming a portion 90 of a circle which when placed adjacent one another form a circular body of greater diameter than each of said wires.

2. In a rail bond, a plurality of wires each of substantially the same sectional area 95 throughout, the end portions of said wires shaped to have a cross-section forming a portion of a circle, said shaped end portions when placed adjacent one another forming a tapering body of substantially circular cross-section, and of greater diameter than each 100 of said wires.

3. In a rail bond, a plurality of wires each of substantially the same sectional area throughout, the end portions of said wires 105 shaped to have a cross-section forming a portion of a circle, said shaped end portions when placed adjacent one another forming a tapering circular body.

4. In a rail bond, a plurality of wires 110 each of substantially the same sectional area throughout, the end portions of said wires shaped to have a cross-section forming a portion of a circle, said shaped end portions when placed adjacent one another forming 115 substantially a frustum of a cone with its base at the end of said wires.

5. In a rail bond, a plurality of wires each of substantially the same sectional area 120 throughout, said wires shaped near each end to have a cross-section forming a portion of a circle, said wires when placed adjacent one another forming substantially a frustum of a cone with its base at the end 125 of each of said wires.

6. In a rail bond, a plurality of wires each of substantially the same sectional area throughout, the end portions of said wires shaped to have a cross-section forming a portion of a circle, a pair of said shaped 130

end portions when placed adjacent one another forming a circular body and aligning the opposite ends of said wires to form a circular body.

5 7. In a rail bond, a plurality of wires each of substantially the same sectional area throughout, said wires shaped near each end to have a cross-section forming a portion of a circle, one of said wires shaped so that when placed adjacent the opposite end of a corresponding wire they together form a tapering circular body of larger diameter than each of said wires.

10 8. In a rail bond, a pair of similar wires of substantially the same sectional area throughout, said wires shaped near each end to have a cross-section forming a portion of a circle, one end of each of said wires shaped so that when placed adjacent 15 the opposite end of the other wire, they form

a tapering circular body of larger diameter than each of said wires, the larger section of said tapering body being at the end of said wires.

9. An article of manufacture consisting of a plurality of wires of uniform diameter, said wires shaped near one end to have a cross-section forming a portion of a circle, and said shaped ends when placed adjacent one another forming a circular body 25 of greater diameter than each of said wires.

10. An article of manufacture consisting of a plurality of wires of uniform diameter, said wires shaped near one end to have a cross-section forming a portion of a circle, 30 said shaped ends when placed adjacent one another forming a tapering circular body with the larger end of the taper at the ends of the wires.

MATTHEW H. LOUGHridge.
